(57) **CLAIM**

The ornamental design for a door lever assembly, as shown and described.

DESCRIPTION

FIG. 1 is a top and front perspective view showing the door lever assembly of the new invention;

FIG. 2 is a front elevation view thereof;

FIG. 3 is a left side view thereof;

FIG. 4 is a right side view thereof;

FIG. 5 is a bottom plan view thereof;

FIG. 6 is a rear elevation view thereof; and,

FIG. 7 is an exploded top and front perspective view thereof corresponding to FIG. 1. The dashed elements in the figures represent background that is not claimed.
